UNITED STATES PATENT OFFICE.

JOHN MAGEE, OF DETROIT, MICHIGAN, ASSIGNOR TO DIAMOND POWER SPECIALTY COMPANY, OF DETROIT, MICHIGAN, A CORPORATION OF MICHIGAN.

SOOT-BLOWER FOR WATER-TUBE BOILERS.

1,162,088.

Specification of Letters Patent. Patented Nov. 30, 1915.

Application filed January 4, 1915. Serial No. 363.

To all whom it may concern:

Be it known that I, JOHN MAGEE, a citizen of the United States of America, residing at Detroit, in the county of Wayne and State 5 of Michigan, have invented certain new and useful Improvements in Soot-Blowers for Water-Tube Boilers, of which the following is a specification, reference being had therein to the accompanying drawings.

10 In water tube boilers having inclined sets of water tubes such, for example, as what are known as Stirling type boilers, there are certain places in the boiler in which the temperature is necessarily close to that of the combustion chamber. In such places it is more or less difficult to maintain fixed soot blowers or cleaners without rapid deterioration or without the use of water jacketed walls or like protected constructions.

20 This invention relates to blowers for boilers having upper and lower members connected by water tubes and divided by baffles so disposed that the tube space is separated into passes that conduct the gases of 25 combustion around and through the boiler from the combustion chamber to the stack.

A feature of the blower is the disposition 30 of jetting members normally exterior to the boiler along the hotter passes working in conjunction with fixed jet tubes arranged across the cooler portions of the tube spaces.

Another feature is the construction of the jetting means for the hotter passes whereby it is readily mounted in the setting of the 35 boiler and easily manipulated from the fire room floor.

The invention consists in the matters hereinafter set forth, and more particularly pointed out in the appended claims.

40 In the drawings, Figure 1, is a view in elevation of a boiler equipped with a blower that embodies features of the invention; Fig. 2 is an enlarged view in detail of a header for the hotter portions of the tube space or 45 passages; Fig. 3 is a view in detail of a preferred form of construction of the header; Fig. 4 is a view in detail showing the disposition of the header in a different position with a corresponding modification of the jet nozzles, and Fig. 5 is a view in detail of a rotary fixed header.

In the drawings, a boiler having a lower member 1 and upper members 2, 3 and 4 connected by a series of water tubes 5, 6 and 55 7, is arranged with the usual exterior boiler

setting 8 and baffles 9 and 10, whereby the tube space of the boiler is divided into the usual passes leading from the combustion chamber 11 to the back connection for the stack. The boiler that is herein illustrated 60 is of the usual Stirling type.

A header 12 with inwardly extending tubular arms 13 is disposed on the exterior of the setting transversely to the initial set 5 of the water tubes in suitably disposed tubular housings 14 inserted in the masonry. A steam line 15 is connected through a suitable control valve 16 with a telescoping intake 17 of the header which permits of normal retraction of the latter well into the housings 70 14, under the influence of spring members 18 two or more of which are in compression between the caps 19 of the housings and the header 12, the arms 13 affording convenient 75 spring keepers. Suitable means, such as the packing gland 20, prevent leakage around the telescoping intake. Oscillatory jet nozzles 21 are appropriately mounted on the bracket head 22 of the arm 13 with suitable connections to a common operating member 80 23 that is mounted on the header 12 and may be turned by a handle 24. The housings 14 are staggered with the adjacent bank of water tubes 5 so that the nozzles 21 direct jets between the tubes and because of the 85 sweeping motion that may be imparted to them when the header is extended under the influence of steam entering the telescoping intake 17, which projects the header bodily 90 inward against the retractive effect of the 95 springs 18, the soot along and between the tubes is dislodged and carried along by the draft or else is deposited on the fire grates.

As shown in Figs. 1 and 2, the header 12 is disposed at right angles to the water tube 95 5 and the jet nozzles 21 are accordingly arranged to swing in planes perpendicular to the axis of the header 12. If however, it is preferred to mount the housings 14 so that the header holds a different relation to the 100 tubes, the movement of the jet nozzles 21, in planes parallel to the water tubes is obtained by appropriately adjusting the connections between the nozzles or nipples and the tube arms 13. For example, the housings may be set in the horizontal courses of the masonry as indicated in Fig. 4, and in such instance the axes of motion of the nipple 105 are disposed substantially perpendicular to the plane of the direction of length 110

of the water tubes. Of course, the nozzles can be of any type preferred which will enable the operator to project jets of steam across the tubes and sweep the jets back and forth in planes parallel to the tubes. This may be done by direct movement of the nozzles or by the employment of slotted openings with stops in the openings to deflect the jets as desired. As herein indicated the jet 5 nozzles 21 are each journaled on a pivot 10 trunnion 25 and each has a segmental rack 26 meshing with a segmental pinion 27 that is oscillated through the medium of a connecting link 28 and a rock arm 29 of the 15 shaft 23 on the header 12. As the brackethead 22 is angularly adjustable on the arm 13 the desired inclination of the trunnion pivot 25, as, for example, seen in Fig. 4, whereby the jets follow the general direction of the 20 tubes, is readily obtained, the link 28 being given the necessary conformation to obtain this result.

One or more other headers dependent upon the size and arrangement of the boiler, 25 may be employed to clean the water tubes and surfaces of the boiler that are in contact with gases of combustion in the hotter portions of the passes. Where, as indicated in Fig. 1, such additional header or headers are 30 arranged at a distance above the floor, a rod 31 and suitable handle 32 may be used for ease of manipulation. If, to avoid long branches of the steam line, the controlling 35 valve 16 is at a height above the floor, a depending cable or chain or other suitable means, indicated at 33, may be employed.

In the cooler passes of the boiler rotatable jet pipes or headers that are indicated in 40 end elevation at 34, are journaled in the setting across the natural spaces of the boiler and are provided with jet openings that project the jets against and between the adjacent tubes and along the same and they also sweep the surfaces of the baffles 9 and 10 45 and other interior surfaces of the boiler. The rotatable jet headers may be of any preferred construction and are shown in one form in Fig. 5 with end bracket 35, bearing 50 36, and jet nozzles 37. They may be of course dry jacketed, water jacketed, sheathed or otherwise protected against the heat which they are forced to encounter from the passing gases. Controlling valves 38 and chains 39 for manually turning these headers from 55 the blower enable them to be directed as desired to sweep and clean all the surfaces against which the jets may be directed therefrom.

As a result of this construction, a blower is 60 obtained which readily cleans any of the portions of a boiler of the type indicated. By proper manipulation of the jetting headers in succession, the soot which is dislodged nearest the fire box or combustion chamber 65 first may be caused to follow the general di-

rection of draft and be blown generally toward the stack although such method of operation is not necessary, although preferable. In the hottest passes, the exterior mounting of the jetting headers or members 70 and their normal retraction (except when in active operation) from the path of the products of combustion, avoids the serious effect of heat on the parts and permits the use of members not jacketed or otherwise protected 75 by a comparatively expensive construction from the effects of the heat.

Obviously, changes in the details of construction may be made without departing 80 from the spirit of my invention and I do not care to limit myself to any particular form or arrangement of parts.

What I claim is:—

1. The combination with a water tube boiler of the Stirling type of a blower comprising horizontally disposed jet pipes rotatably mounted across some of the passes and adapted to direct jets between and over the water tubes thereof and the surfaces of the boiler that are in contact with the gases of combustion, and headers on the exterior movable toward the interior of the boiler setting, transversely disposed to the adjacent water tubes and each provided with a set of jetting means adapted to be manipulated when the header is moved toward the interior of the boiler setting for sweeping across and longitudinally of the tubes. 95

2. A blower for a water tube boiler having top and bottom members, water tubes connecting the members and baffles dividing the space of the tubes into passes, comprising rotatable jet pipes mounted across some of the passes and adapted to direct jets between and over the water tubes thereof and the surfaces of the boiler that are in contact with the gases of combustion, headers transversely disposed to the adjacent water tubes of other passes on the exterior of the boiler and adapted to be steam projected toward the 100 interior of the boiler setting, a series of jetting means on each header adapted when the latter is moved toward the interior of the boiler setting to direct jets of steam across, between and along the tubes in the 105 general direction thereof, means for controlling the rotatable pipes and means exterior to the boiler for operating each series of jetting means. 110

3. In a water tube boiler having top and bottom members, water tubes connecting the members and baffles dividing the tube space into passes, a blower comprising one or more rotatable jet pipes journaled across the passes of the boiler and adapted to direct 125 jets between and over the water tubes and surfaces of the passes in which they are situated, and side blowers on the boiler setting adjacent certain passes of the boiler, adapted to normally maintain themselves out 130

of the path of flow of gases in the boiler, when the blower is inactive, and to automatically extend into operative relation to the water tubes and surfaces of the boiler
 5 that are in contact with the gases of combustion when cleaning fluid under pressure is introduced into said headers, a series of jetting means on each of said headers adapted to sweep the water tubes and surfaces
 10 of the boiler that are in contact with the gases of combustion when oscillated and manually operable means exterior to the boiler for controlling and directing the series of side headers and for manually operating and controlling the rotatable header.

4. The combination with a water tube boiler having top and bottom members connected by water tubes and provided with baffles that divide the tube space into passes
 20 together with a setting therefor, of a blower having rotatable jet pipes journaled across certain of the passes of the boiler and adapted to direct jets between and over the water tubes and surfaces thereof that are in contact with the gases of combustion and exterior headers mounted in the boiler setting and each provided with a series of jetting means adapted to be moved with the headers toward the interior of the boiler setting,
 25 together with manually operable means both for manipulating the rotatable headers and for directing the jet producing means of the side headers to sweep the water tubes and surfaces of the boiler in contact with the gases of combustion in planes substantially parallel to the direction of length of the tubes thereof.

5. In a water tube boiler having top and bottom members connected with water tubes disposed in series and provided with baffles dividing the tube space into passes, a blower

comprising side headers mounted on the exterior of the boiler adjacent the passes nearer the combustion chamber of the boiler, each provided with a series of jetting means
 45 adapted to be moved together with a header toward the boiler and arranged to direct jets between or along the tubes in the general direction thereof, and rotatable jet pipes journaled across the passes that are more
 50 remote from the combustion chamber and are adapted to direct jets between, over and along the water tubes and surfaces of the boiler that are in contact with the gases of combustion.

6. In a water tube having top and bottom members, tubes connecting the members and baffles dividing the tube space into passes, a blower comprising rotatable jet pipes in the passes that are more remote
 60 from the fire box, adapted to direct jets between and over the water tubes and surfaces of the boiler that are in contact with the gases of combustion, housings in the side of the boiler adjacent the hotter passes, headers
 65 having inwardly extending arms reciprocable in the several housings, jetting means on the inner ends of the arms adapted to be operated simultaneously to direct jets between and along the tubes and the surfaces of the passes in planes substantially parallel to the direction of length of the tubes and means exterior to the boiler for manipulating the rotatable jet pipes and the header jetting means.

In testimony whereof I affix my signature in presence of two witnesses.
